ELECTRIC EXTENSION CORD PLUG

Albert C. Hass, Elmhurst, Ill.

Application December 23, 1948, Serial No. 66,925

2 Claims. (Cl. 173—360)

1

This invention relates to improvements in plugs for electric extension cords, and more particularly to a plug for use with a screw socket, such as a light bulb socket, having a cylindrical, screw-threaded shell therein.

It is among the objects of the invention to provide an improved electric extension cord plug which may be inserted, without turning, into a conventional screw socket having a screw-threaded, cylindrical shell, and firmly engaged in said socket against accidental removal, which makes an effective electrically conductive contact with the socket shell and is strong and durable in construction, economical to manufacture, neat and attractive in appearance, and easy to use.

Other objects and advantages will become apparent from a consideration of the following description and the appended claims in conjunction with the accompanying drawings, wherein:

Figure 1 is a longitudinal elevation of an extension cord plug illustrative of the invention operatively associated with a conventional screw socket, a portion of the socket being broken away and shown in cross-section to better illustrate the association of the plug with the socket;

Figure 2 is a longitudinal elevation of the plug illustrated in Figure 1 with the plug turned through an angle of 90-degrees from the position illustrated in Figure 1;

Figure 3 is a longitudinal, medial cross-section through the improved plug taken in a plane substantially parallel to the plane of the paper with the plug in the position illustrated in Figure 2;

Figure 4 is a transverse cross-section taken substantially on the line 4—4 of Figure 1;

Figure 5 is a longitudinal elevation of the upper-half portion of the plug as illustrated in Figure 4;

Figure 6 is a longitudinal elevation of the lower-half portion of the plug as illustrated in Figure 4, portions being broken away and shown in cross-section to better illustrate the construction of the plug;

Figure 7 is a view similar to Figure 5 of a fragmentary lower portion of the plug showing the parts in a different operative position from that illustrated in Figure 5;

Figure 8 is a perspective view of an encircling band for the portion of the plug received in the screw socket;

Figure 9 is a perspective view of a dog for releasably locking the plug in the socket;

Figure 10 is a perspective view of a contact spring constituting an operative component of the plug; and

Figure 11 is a perspective view of a split spring ring which retains the two portions of the plug in operative assembly.

With continued reference to the drawings, the 5 conventional screw socket, generally indicated at 10, has an outer, cylindrical shell 11 conventionally formed of thin metal, such as brass, although it may be formed of ceramics or other suitable material, a body 12 of insulating material 10 in the outer shell carrying a center contact 13, an inner cup or shell 14 formed of electrically conductive material, such as thin, rolled brass, and provided with screw threads 15, and an insulating shell or cylinder 16 interposed between 15 the outer shell 11 and the inner shell 14. The line or power wires are connected respectively to the center contact 13 and the inner shell 14 of the screw socket. Such a socket is conventionally used to receive a lamp bulb, but, when provided 20 with a suitable plug, may be used for other purposes, such as for supplying electric current to a table lamp or floor lamp, an electric iron, toaster, or other appliance.

The extension cord socket has an elongated 25 shell, generally indicated at 17, of electrically insulative material, such as hard rubber or synthetic resin plastic, and is longitudinally divided into two substantially similar parts or halves 18 and 19, as clearly illustrated in Figures 2, 4, 5, and

30 6. The shell 17 is hollow and of circular cross-section and includes a reduced cylindrical portion 20 receivable in the inner shell 14 of the screw socket, and having a diameter considerably less than the internal diameter of the socket, a large cylindrical portion spaced from the reduced portion 20, and a cylindrical step portion 22 between the reduced portion 20 and the large end portion 21.

Internally, the plug shell is provided with an 35 elongated, substantially cylindrical cavity within which are disposed two spaced-apart, substantially parallel guide ribs 23 which extend longitudinally of the interior of the shell from the outer end wall 24 of the large portion 21 to a location within the step portion 22 and spaced from the reduced portion 20. The reduced portion 20 is provided in its cylindrical wall with a pair of diametrically-opposed slots 25 which communicate with the interior concavity of the shell and 40 is also provided with an end wall 26 secured to or formed integrally with the part 19 and underlying the smaller end of the part 18 of the shell.

The reduced portion 20 of the shell is annularly recessed and a circular metal band 26 surrounds the reduced portion of the shell within

this recess and is provided with slots 27 registering with the slots 25 in the reduced end portion of the shell. The large portion 21 of the shell is also provided with an annular groove 28 and a split, spring ring 29 is disposed in the groove 28 surrounding the large portion of the shell. This spring ring is provided at its ends with inwardly-directed tongues 30 receivable in a notch provided in the shell within the groove 28, so that the ring firmly locks the two parts 18 and 19 of the shell together when operatively disposed in the groove 28.

A center contact 31 is secured in the end wall 26 for contact with the center contact 15 of the socket, and a pair of binding posts 32 and 33 are secured in the cavity of the plug within the part 19. A conductor 34 connects the center contact 31 with the binding post 32 which is also connected with one wire 35 of the extension cord 36. The other wire 37 of the extension cord is connected with the binding post 33 and the two wires 35 and 37 are tied together in an Underwriters' knot 38 within the cavity in the part 19 to prevent the cord from pulling out through the hole 39 provided in the part 19 for the reception of the cord.

A contact leaf spring 40 is secured in the part 19 and is electrically connected to the binding post 33. This leaf spring extends longitudinally of the plug and is positioned contiguous to the open side of the space between the two guide ribs 23, when the two parts of the plug are operatively assembled. A plunger 41, preferably of square or rectangular cross-sectional shape, is slidably mounted between the two guide ribs 23, and in frictional engagement with the spring 40. This plunger is of electrically conductive material, and a handle 42 of electrically insulative material is secured to one end of this plunger by a stem 43 which extends through an opening 44 in the part 18 of the plug shell.

A pair of socket-engaging dogs 45 are mounted in the reduced and step portions of the shell, and have serrated end portions 46 projectible through respective slots 25 in the reduced portion of the shell and through respective slots 27 in the band 26 to engage in the threads 15 in the inner shell 14 of the socket, as is clearly illustrated in Figure 1. A pivot pin 47 extends transversely through the reduced portion of the shell adjacent the step portion 22 and through registering apertures in the two dogs 45 to pivotally connect the dogs to each other and to the shell, the two dogs being crossed-over at the pivot point, as is clearly illustrated in Figures 5 and 7.

A pair of links 48 are each pivotally connected at one end to the end of the plunger 41 opposite the end of the plunger to which the handle 42 is attached, by a common pivot pin 49, and are pivotally connected at their opposite ends to the adjacent ends of respective dogs 45 by respective pivot pins 50.

With the parts in operative assembly, as illustrated in Figures 1 and 2, when the handle 42 is pulled outwardly of the socket shell 17, the two links 48 are brought to the angularly-disposed, relative position illustrated in Figure 5, and the serrated ends 46 of the two dogs 45 are retracted through the corresponding slots 25 in the reduced, cylindrical end portion of the plug shell. The reduced portion of the plug may now be inserted into a screw socket, such as is illustrated in Figure 1. After the reduced portion of the plug is disposed within the inner shell of the screw socket, the handle 42 is forced inwardly of the

shell spreading the serrated end portions 46 of the two dogs into firm and electrically conductive contact with the inner shell of the socket. When the handle is forced inwardly to spread the serrated ends of the dogs, the two links 48 are brought to a position of relative alignment, as illustrated in Figure 7, so that the dogs are releasably locked in engagement with the socket inner shell and the plug cannot be removed from the socket until the handle 42 is manually pulled outwardly of the plug shell. When it is desired to remove the plug from the socket, the handle 42 is pulled outwardly, retracting the serrated ends 46 of the dogs, whereupon the plug is easily movable out of the socket.

The invention may be embodied in other specific forms without departing from the spirit or essential characteristics thereof. The present embodiment is, therefore, to be considered in all respects as illustrative and not restrictive, the scope of the invention being indicated by the appended claims, rather than by the foregoing description, and all changes which come within the meaning and range of equivalency of the claims are, therefore, intended to be embraced therein.

What is claimed is:

- An electric extension cord plug comprising a hollow, elongated shell of electrically insulative material longitudinally split into two substantially similar parts and having at one end a reduced cylindrical portion receivable in a conventional screw socket and provided with an end wall, said shell having a pair of guide ribs there-in spaced from said reduced portion and a pair of opposed, longitudinally-extending slots in the cylindrical wall of said reduced portion, a center terminal extending through said end wall, a pair of spaced-apart binding posts for the wire ends of an extension cord, said binding posts being disposed in said shell near the end of the latter opposite said reduced portion, means electrically connecting said center terminal to one of said binding posts, a leaf spring connected to one of said binding posts and extending longitudinally of said shell contiguous to said guide ribs, a plunger of electrically conductive material slid-able between said guide ribs in contact with said spring, a handle of electrically insulative material secured to one end of said plunger and extending out of the end of said shell opposite said reduced portion, a pair of socket-engaging dogs of electrically conductive material in said shell having serrated end portions projectible through respective slots in said shell reduced portion to engage socket screw threads when said reduced portion is inserted into a screw socket, a pivot pin pivotally connecting said dogs together and to said shell, a pair of links of electrically conductive material each pivotally connected at one end to the end of said plunger opposite said handle and at its opposite end to the adjacent end of a respective dog to spread the serrated end portions of said dogs upon movement of said handle inwardly of said shell, said links having a relatively aligned operative position to releasably lock said dogs in spread condition, a band surrounding the reduced portion of said shell, and a split spring ring surrounding said shell at a location spaced from said reduced portion to hold the two parts of said shell in operative assembly.
- An electric extension cord plug comprising an elongated, hollow shell longitudinally split into two substantially similar parts, said shell having at one end a reduced cylindrical portion receivable in a screw socket and provided with op-

positely-disposed slots in its cylindrical wall, a pair of dogs of electrically conductive material pivotally mounted in said shell and having serrated end portions projectable through respective slots in said reduced portion to engage the inner surface of a screw socket receiving said reduced portion of said plug, a plunger slideable in said plug shell, means pivotally inter-connecting the adjacent ends of said plunger and said dogs for pivotal movement of said dogs upon longitudinal movement of said plunger in said shell, a handle secured to the end of said plunger opposite the dog-connected end of the latter and extending through the end of said shell opposite said reduced shell portion, an end wall on said reduced portion, a center contact carried by said end wall, a pair of binding posts in said plug shell receiving respective wires of an extension cord, and means in said shell electrically connecting said center contact and said plunger to respective binding 10 15 20

posts, said means pivotally interconnecting said handle and said dogs comprising a pair of links each pivotally connected at one end to said handle at one end of the latter and pivotally connected at their opposite ends to said dogs respectively, said links having a longitudinally aligned operative position in which they lock said dogs in projected position.
